UNITED STATES PATENT OFFICE.

EDWARD W. HOWELL, OF NEW YORK, N. Y., ASSIGNOR TO HERBERT L. MAY, OF NEW YORK, N. Y.

REFRIGERATING APPARATUS.

SPECIFICATION forming part of Letters Patent No. 702,062, dated June 10, 1902.

Application filed June 3, 1901. Serial No. 62,824. (No model.)

To all whom it may concern:

Be it known that I, EDWARD W. HOWELL, a citizen of the United States, and a resident of New York, in the county and State of New York, have invented a certain new and useful Improvement in Refrigerating Apparatus, of which the following is a specification.

My invention relates to refrigerating apparatus.

10 It has for its object to improve and simplify apparatus for artificial refrigeration, and especially the means employed for distilling the gas—ammonia, for example—from the strong liquor and for absorbing the expanded 15 gas after refrigeration into the weak liquor; also, to render such apparatus more efficient and rapid in operation and more economical.

It consists of the novel devices herein shown and described.

20 My invention is applicable either to a still for distilling gas, such as ammonia, from strong liquor or to an absorber for reabsorbing the expanded gas after refrigeration has taken place back into the weak liquor, and 25 in the drawings accompanying this specification and forming part hereof and in the description I have shown and described my invention as applied to an apparatus which is equally well adapted for both distillation and 30 absorption.

In the said drawings I have shown the preferred form or embodiment of my invention, which I will now proceed to describe.

Referring to the form of my invention 35 shown in the drawings, Figure 1 is a front view of an apparatus embodying my invention. Fig. 2 is a plan view of the same with the refrigerating-coil and its surrounding box omitted; and Fig. 3 is a vertical diagrammatic section taken through the different parts of the apparatus, although not taken on the same vertical plane in all parts.

40 In my apparatus, as shown in the drawings, the same parts can be used either as a still or as an absorber, and in practice I use such parts at one time as a still and later as an absorber, and, as shown in the drawings, I prefer to employ two distinct sets of such stills or absorbers, as clearly shown in Fig. 2. 45 Each still or absorber is composed of two or more chambers, which are connected with

each other, so as to permit a free flow of the liquor back and forth between the chambers in order to create and maintain a circulation to aid in the distillation of the gas 55 from the strong liquor or its absorption in the weak liquor. In practice I prefer to use for each still or absorber three distinct chambers, as shown in Fig. 3. One of these, the chamber 1, has connected with it means for heating or cooling the liquor in that chamber. The other chambers 2 I will refer to herein as "equalizing-chambers." These equalizing-chambers are arranged above the lower chamber 1 and are connected 60 to each other by a pipe 3. I preferably connect each equalizing-chamber with the lower chamber by means of at least two pipes, which have their mouths opening into one of the said chambers at different heights to aid in 65 starting and maintaining a circulation of liquor between the chambers. In the form shown in the drawings I have shown three pipes connecting each equalizing-chamber with the lower chamber 1. Of these pipe 4 runs from a point near the bottom of chamber 1 up into the top of chamber 2 and opens into said chamber above the top of the liquor. Preferably it runs into and through the top 70 of chamber 2 and preferably has a mouth 75 above or at about the height of the liquor in chamber 2, as shown in Fig. 3, for the escape of the flow passing up pipe 4, and just above the mouth of this upper part of pipe 4 are also preferably provided a row of holes 80 85 5 to also permit the escape of gas from the pipe into the upper part of chamber 2. The form of this pipe and the manner of its opening into the top of chamber 2 can be varied as desired. 6 is another pipe connecting each 90 equalizing-chamber with the chamber 1, and, as shown, the mouths of this pipe open at the top of chamber 1 and part way up in chamber 2. The third pipe connecting the equalizing-chamber with the pipe 1 is pipe 7, which 95 runs from the bottom of chamber 2 to the top of chamber 1. The mouths of these various pipes are open, and some of them are, as shown, arranged at different heights in the chambers. I will first describe the operation 100 of these parts when used as a still.

Any suitable means may be employed in

connection with chamber 1 for heating the strong liquor therein. As shown, I employ a row of burners 8. These heat the strong liquor at and around the bottom of chamber 5 1 first, causing the gas to be liberated first at that point and producing a flow of heated gas up pipes 4 into the upper part of equalizers 2, heating at once the cold gas in the top of the equalizers remaining unabsorbed from 10 the previous use of the apparatus as an absorber and also aiding in heating the liquor in the equalizers. This heating of the gas at the top of the equalizers at the beginning of the operation is of special value, as a body of 15 cold gas at the top of a still materially retards the process of distillation. By my device heat developed at the bottom of the apparatus is almost immediately conveyed to the top of the still with the above beneficial 20 result. As the liquor in chamber 1 becomes more generally heated an upward flow of gas and heated liquor begins in pipe 6 and a downward flow of colder liquor through pipe 7. A circulation is thus started which is 25 maintained during the entire operation of distilling the gas, and this circulation materially assists in the distillation of the gas from the liquor. Distillation of the gas thus proceeds rapidly and efficiently. When the 30 requisite pressure is obtained, cock 28 and cock 9 are opened, and the heated gas passes through pipes 10 and 11 into condenser 12, where it is cooled by a spray of water proceeding from the perforated pipe 13 and in 35 the usual manner is condensed into liquid anhydrous ammonia, and thence passes into receiver 14. From here it passes in the usual way through pipe 15, controlled by cock 16, into the refrigerating-coils 17 in refrigerator 40 18, where it is expanded into a gas and produces cold in the usual way. Cock 19 controls the flow of the liquid anhydrous ammonia. The expanded cold gas thence proceeds back through pipe 20 preferably to the 45 other set of combined still and absorber, where it is absorbed by the weak liquor, as will be presently described.

Both sets of combined stills and absorbers may be used together as stills or absorbers; 50 but in practice I prefer to alternate their use, first using one set as a still and the other set as an absorber, and so on.

In Fig. 3 I have shown the chambers 1 and 22 as provided with strong liquor preparatory 55 to distillation and receiver 14 as having a supply of liquid anhydrous ammonia, obtained by distillation from the other set of chambers and preparatory to refrigeration and absorption. Each set is used as an absorber in the 60 following manner: The cold gas from the refrigerating-coils is permitted by cock 21 of pipe 20 to pass from that pipe into and along the bottom of chamber 1. It escapes into the weak liquor from numerous small openings 65 22 in the part of pipe 20 that projects into chamber 1, as shown in Fig. 3. The weak liquor in chamber 1 is cooled by means of cold

water passing through pipe 13, which in said chamber 1 is formed into coils in the usual manner. This flow is controlled by cocks 23 70 24. Any other suitable means may be used for cooling the weak liquor, if desired. The weak liquor in chamber 1 is thus cooled before the liquor in equalizers 22, and it readily and quickly absorbs the gas. As the liquor 75 becomes more and more saturated with the gas it rises and passes up through pipes 6 6 into equalizers 2, the weaker liquor passing down through pipes 77 into chamber 1. A circulation is thus started which is maintained 80 during the entire operation of absorption. This circulation materially aids in the work of absorption and renders it much more efficient than where a single chamber is employed for the purpose or where chambers are employed which are separate from each other or between which no free flow of the liquor is possible or is maintained. This circulation proceeds until the gas has been entirely absorbed. The said set of apparatus is then ready to be 90 again used as a still for distilling the gas from the now strong liquor. In my improved apparatus means are provided to permit a free flow of the liquor back and forth between the chambers, so that at all times during the process of distillation or absorption a circulation 95 is maintained between the chambers. The pipes to accomplish this may be arranged differently from those shown in the drawings without departing from my invention so long as circulation between the chambers is permitted. I find in practice, however, that this circulation is materially aided by causing the mouths of some of the pipes to open at different heights in one or more of the chambers, 100 105 and I also prefer in practice three pipes, connecting each equalizing-chamber with the lower chamber, although these are not essential to my invention in some of its aspects. The number of equalizing-chambers may be varied and be diminished or increased from that shown and the equalizing-chamber and that with which the heating and cooling means are connected may be differently located and arranged from those shown. If desired, the 110 coils of pipe 13 in said chamber 1 may be used for heating the strong liquor by passing hot water or steam or other suitable heating agent through them. Pipe 3 tends to maintain the level of the liquor the same in both equalizers. 115 25, 26, and 27 are the usual gages.

By means of my improved apparatus gas can be distilled from strong liquor or be absorbed by weak liquor in a refrigerating apparatus with great rapidity and at little cost, 120 125 and the refrigerating apparatus is efficient, simple, and inexpensive.

Many other changes and modifications than those suggested above can be made in the apparatus shown and described in the drawings 130 and specifications herein without departing from my invention.

The process of distilling and absorbing gas in a refrigerating apparatus herein shown and

described is not claimed in this present application; but it is not abandoned, as I intend to make it the subject-matter of another application.

5. What I claim as new, and desire to secure by Letters Patent, is—

1. In apparatus adapted for use either as the still or absorber of refrigerating apparatus the combination of a chamber for heating or cooling the liquor, two equalizing-chambers arranged above the heating or cooling chamber so that the entire body of liquor in each equalizing-chamber shall be at a higher level than the body of liquid in the 15 heating or cooling chamber and pipes freely connecting each of the equalizing-chambers with each other and with the lower chamber, and means connected only with the lower chamber for heating or cooling the liquor 20 therein, whereby a circulation of the liquor will be established back and forth among the chambers, and the distillation of the gas from the liquor or its absorption therein will thereby be assisted.

25. 2. In apparatus adapted for use either as the still or absorber of refrigerating apparatus, the combination of a chamber for heating or cooling the liquor, two equalizing-chambers arranged above the heating or cooling chamber, a pipe connecting the equalizing-chambers with each other, two pipes freely connecting each equalizing-chamber with the lower chamber and having their mouths opening into one of the said chambers at different heights therein to permit a 30 free flow of the liquor back and forth between each equalizing-chamber and the lower chamber, whereby a circulation of the liquor will be established back and forth among the 35 chambers, and the distillation of the gas from the liquor or its absorption therein will thereby be assisted.

3. In apparatus adapted for use either as the still or absorber of refrigerating apparatus, the combination of two chambers for the liquor arranged one above the other and connected with each other by means of three 45 pipes, one pipe running from near the bottom of the lower chamber to the top of the

upper chamber, and opening therein another 50 of the said pipes running from the top of the lower chamber and having its mouth opening into the upper chamber at a point part way between the top and the bottom of the said chamber, and the third pipe running from 55 the top of the lower chamber to the bottom of the upper chamber, and means connected with the lower chamber for heating or cooling the liquor therein, whereby a circulation of the liquor will be established back and 60 forth between the two chambers, and the distillation of the gas from the liquor or its absorption therein will thereby be assisted.

4. In apparatus adapted for use either as the still or absorber of refrigerating apparatus, the combination of a chamber for heating or cooling the liquor, two equalizing-chambers arranged above the heating or cooling chamber, a pipe connecting the equalizing-chambers with each other, and three pipes 70 connecting each equalizing-chamber with the lower chamber, one pipe running from near the bottom of the lower chamber to the top of the said equalizing-chamber and projecting downward therein and provided in the 75 said downward projection with openings for the escape of gas, another of the said pipes running from the top of the lower chamber and having its mouth opening into the said equalizing-chamber at a point part way between the top and the bottom of the said chamber, and the third pipe running from the top of the lower chamber to the bottom of the said equalizing-chamber, and means connected with the lower chamber for heating 80 or cooling the liquor therein, whereby a circulation of the liquor will be established back and forth among the chambers, and the distillation of the gas from the liquor or its absorption therein will thereby be assisted. 90

In testimony whereof I have signed my name to this specification in the presence of two subscribing witnesses.

EDWARD W. HOWELL.
